(57) **CLAIM**

The ornamental design for a wrapping sheet for packaging an electronic device, as shown and described.

DESCRIPTION

This application is related to U.S. application Ser. No. 29/891,237, filed on even date herewith, entitled "Wrapping Sheet for Packaging an Electronic Device" and U.S. application Ser. No. 29/891,238, filed on even date herewith, entitled "Wrapping Sheet for Packaging an Electronic Device", both of which are hereby incorporated by reference as if set forth in their entirety herein.

FIG. 1 is a top view of a wrapping sheet for packaging an electronic device showing my new design;

FIG. 2 is a bottom view thereof;

FIG. 3 is a front side view thereof;

FIG. 4 is a rear side view thereof;

FIG. 5 is a right side view thereof; and,

FIG. 6 is a left side view thereof.

The shade lines indicate the character and contour of the surfaces represented, not to be confused with surface ornamentation.

The shading for the circular label in FIG. 1 represents an opaque element and is not to be confused with surface ornamentation. The circular label is disposed on a top portion of the wrapping sheet for packaging an electronic device without claiming any particular shade or color. The different shading for the wrapping sheet for packaging an electronic device represents a translucent material in contrast to the opaque shading in FIG. 1 and is not to be confused with surface ornamentation. The dashed lines depict an electronic device that is wrapped by the wrapping sheet for packaging an electronic device, wherein the electronic device forms no part of the claimed device. Portions of the dashed lines in the drawings appearing behind the wrapping sheet for packaging an electronic device are

(Continued)

farther apart to represent an obscured appearance through the translucent layer(s) of the wrapping sheet for packaging an electronic device.
